DESIGN FOR A DOOR KNOCKER

Joseph Stephens, Inglewood, Calif.

Application November 30, 1945, Serial No. 124,216

Term of patent 7 years

(Cl. D10—7)

To all whom it may concern:

Be it known that I, Joseph Stephens, a citizen of the United States, residing at Inglewood, in the county of Los Angeles and State of California, have invented a new, original, and ornamental Design for a Door Knocker, of which the following is a specification, reference being had to the accompanying drawing, forming a part thereof, and in which:

Fig. 1 is a front elevational view of a door knocker, showing my new design.

Fig. 2 is a side view of the door knocker.

Fig. 3 is a vertical sectional view taken on the line 3—3 of Fig. 1.

Fig. 4 is a horizontal sectional view taken on the line 4—4 of Fig. 1.

I claim:

The ornamental design for a door knocker, as shown

JOSEPH STEPHENS.
